REINFORCING BAR FOR CONCRETE

Charles Stratton Davis, Pittsburgh, Pa.

Application January 20, 1932, Serial No. 587,699

1 Claim. (Cl. 72—111)

The following is a full, clear and exact description, reference being had to the accompanying drawing, forming part of this specification, in which:

5 Figure 1 is an isometric projection showing one form of bar made in accordance with my invention;

Figure 2 is a similar view of a modified form;

10 Figure 3 is an enlarged cross sectional diagram of the form of Figure 1.

Figure 4 is a similar diagram of the form of Figure 2;

15 Figure 5 is an isometric projection of a portion of the breakdown bar for rolling the form of Figure 1 in one pass of rolling mill; and

Figure 6 is a partial front elevation of a portion of the rolls for showing the pass for rolling the form of Figure 1.

20 My invention relates to bars for reenforcing concrete, and is designed to provide a bar of the same cross sectional shape throughout to avoid distortions of stress lines; to have a ratio of perimeter to cross sectional area greater than that of a square or round bar of the same cross 25 sectional area; and to be rolled under good rolling mill practice.

One of the main requirements of such bars 30 is that its bond strength—the strength of the bond between the bar and the concrete in which it is embedded—shall be sufficient to develop its full tensile strength. The length of such embedded bar depends upon its unit tensile strength, its unit bond strength, and its ratio of perimeter to cross sectional area. In the 35 earlier stages of this art, plain round and plain square bars were used, and later, in order to reduce the length of bars required to develop full tensile strength, square bars were twisted and bars of different shapes otherwise deformed.

40 Plain square or round bars are free from the objection to distortion of stress lines, but the ratio of perimeter to cross sectional area is relatively low, and hence longer bars are required to develop full tensile strength from their 45 bond strength with concrete.

Twisted bars are more expensive to manufacture than plain bars and, unless annealed, lack homogeneity, since the outer fibres are stressed beyond their yield points in giving a 50 permanent twist, while the central fibres are not altered. The stressing of the outer fibres beyond their yield points changes their stress-strain curves under test, and hence the metal in such twisted bars lacks the desired uniformity 55 of character. The stress lines in the outer fibres

of a twisted bar follow the spiral lines of twist, while those of the central fibres are straight along the axis, which results in lack of uniformity of stress lines.

Deformed bars are more expensive to manufacture than plain bars on account of the extra expense of preparing the rolls which wear rapidly. Bars having raised deformations contain material not effective for tensile stresses and hence are not economical. The stress lines in 60 a deformed bar are distorted by its deformations and consequently lack uniformity. The development of bond strength through these deformations is not uniformly distributed, and hence the concrete is liable to over-stressing at points of 65 deformation.

70 My invention is designed to provide a bar having the same cross sectional shape throughout its length to avoid distortion of stress lines, but having a ratio of perimeter to cross sectional 75 area greater than that of a square bar, and of course, greater than that of a round bar; so that the length of bar required for bond strength to fully develop its tensile strength may be as short as possible, while at the same time it may 80 be rolled in a rolling mill under ordinary practice.

To that end, the bar has throughout its length 85 a cross sectional shape of a 6-pointed star with the points located at the apices of a circumscribing hexagon—either regular or irregular—the reentrant angles Z Figure 3 between these points being sufficiently small to give a ratio 90 of periphery to cross sectional area greater than that of a square bar and yet provide the proper draft or taper for rolling.

In the preferred form shown in Figures 1 and 3, the bar 2 has six points which are coincident with the apices of the regular circumscribing hexagon at the points $a^1, a^2, a^3, a^4, a^5, a^6$. In 95 the diagram of Figure 3, o is the center of the star. The lines $a^1—a^4, a^2—a^5$, and $a^3—a^6$ through the center are long diameters, each twice the radial length of the star. The lines $b^1—b^4, b^2—b^5$, and $b^3—b^6$, each through the center of 100 the star, are short diameters, each twice the short radial length of the star. The angles x between the peripheral lines of the star and the sides of the hexagon are all the same, and these angles are sufficient to provide a ratio of perimeter to cross sectional area greater than the corresponding ratio of a square bar, so that the ratio of surface area to volume is greater than that in a square bar. These angles, however, are 105 limited to give proper draft or taper for rolling 110

purposes, so that any two lines of the periphery of the star, between which there are two intervening lines forming a reentrant angle will be sufficiently divergent to conform to good 5 rolling mill practice, so that any long diameter such as a^2-a^5 may lie along the line of contact, $d-d$, Figure 6, between the rolls.

I prefer that the angles x be less than 30° (28° as shown in Figure 3), so that where the 10 line a^2-a^5 coincides with the line of contact between the rolls, the lines a^1-b^1 and a^6-b^5 and also a^3-b^2 and a^4-b^4 shall be sufficiently divergent to give the draft or taper required for 15 good rolling mill practice; but these angles shall not be less than 12° in order that the ratio of periphery to cross sectional area shall always exceed the ratio of perimeter to cross sectional area of a square bar.

The perimeter of a round bar having a cross 20 sectional area of one inch is 3.555 inches; that of a square bar of the same area is 4.000 inches; and that of my preferred form with the 28° angle shown in Figure 3 is 5.064 inches, so that its ratio of perimeter to cross sectional area is 25 42.5% greater than that of a round bar and 26.6% greater than that of a square bar.

In the form of Figures 2 and 4, the irregular 30 star section for 2^a has its points a^1, a^2, a^3, a^4, a^5 and a^6 at the corners of an irregular circum- 35 scribing hexagon with its long diameter a^2-a^5 falling along the line of contact between the rolls. The angles y of Figure 4 between the lines of the periphery of the star and the sides of the irregular circumscribing hexagon shall not be 40 larger than is necessary to make the lines a^3-b^2

and a^4-b^4 , and also a^1-b^1 and a^6-b^5 sufficiently divergent to provide draft or taper for 80 rolling under good rolling mill practice; but they shall be large enough to make the ratio of perimeter to area of the star greater than that of a rectangle of the same area and having the same ratio of width to height as the irregular star.

The breakdown bar 5 for the preferred form of 85 Figures 1 and 3 is preferably of the shape shown in Figure 5, so that when turned on edge with its longer axis vertical the reinforcing bar may be rolled therefrom in one pass as shown in Figure 6. The breakdown bar for the form of 90 Figures 2 and 4 will, of course, be correspondingly modified.

The advantages of my invention lie in its high 95 bond strength per unit of length, due to its great ratio of perimeter to cross sectional area, resulting in a shorter length of bar than with either plain square or round bars; in its freedom from distorted stress lines; in the uniformity of its bond strength per unit of length; and in that it may be produced at a low cost, due to its being of the same cross sectional shape 100 throughout and easily rolled.

Variations may be made in the angles, size, etc., without departing from my invention.

I claim:

A reinforcing bar for concrete being in the 105 form of a prism between any two parallel cross sectional planes whose uniform cross section is that of a 6-pointed star.
